UNITED STATES PATENT OFFICE.

JOHN P. GRUBER, OF NEW YORK, N. Y.

IMPROVEMENT IN APPARATUS FOR FORCING WATER BY PNEUMATIC PRESSURE.

Specification forming part of Letters Patent No. 43,770, dated August 9, 1864.

To all whom it may concern:

Be it known that I, JOHN P. GRUBER, of New York city, county and State of New York, have invented a new and useful Improvement in Water-Works for Supplying Houses or Fountains with Water; and I do hereby declare that the following is a full, clear, and exact description thereof, reference being had to the accompanying drawings, making a part of this specification, in which—

Figure 1 is a side elevation of my apparatus arranged with one water reservoir. Fig. 2 is an end elevation of Fig. 1. Fig. 3 is a longitudinal section through the two reservoirs or chambers. Fig. 4 is a view in detail of the induction-passage which is applied to the water-chamber of Figs. 1, 2, and 3.

Similar letters of reference indicate corresponding parts in the several figures.

The object of my invention is to obtain an apparatus by means of which condensed air can be practically and conveniently employed, either upon a large or a small scale, for the purpose of forcing water or other liquid to elevated points, as will be hereinafter described.

The nature of my invention consists in an apparatus which is composed, essentially, of an air-vessel for containing condensed air, an air engine for condensing air, a liquid vessel for containing the liquid to be acted upon by the condensed air, and a valve applied to the latter vessel, which opens inward and admits of the introduction of liquid into the said vessel when the pressure of the condensed air is cut off—removed.

My invention also consists in providing the liquid-receiver of an apparatus, which will be hereinafter described, with means whereby liquid can be forced or introduced, when desired, into said receiver, whether the pressure in the same be removed or not.

My invention further consists in a valve which is so constructed and applied to the liquid-vessel of a forcing apparatus or "fountain" that this valve can be made to operate automatically, and thus allow said vessel to be refilled at pleasure in localities where it might not always be desirable or convenient for a person to get at it, all as will be hereinafter described.

To enable others skilled in the art to make

and use my invention, I will describe one method of carrying it into effect.

In the accompanying drawings, A represents a condensing-pump, which is constructed with a solid piston and a valve opening upward in its bottom for the entrance of air into the pump when the piston is drawn up. This air pump or condensing engine may be constructed in any other suitable manner, either as a single-acting engine or a double-acting engine, and it may be worked by manual power or operated by other engines. At or near the bottom of the condensing-pump is a pipe, B, which leads into a strong reservoir, C, which should be made air-tight, so that it will retain within it, when desired, the air which is supplied by the pump A. This reservoir, which is to contain highly-condensed air, should be constructed in such manner that it will safely contain all the air which can be forced into it by the pump A, and, if desired, a safety-valve may be applied to it, by which the amount of pressure can be readily ascertained.

From the reservoir C one or more pipes, D, lead off to water-reservoirs, one of which, E, is represented in Figs. 1 and 3. The reservoir E is also made very strong and air-tight, and it may be made of any suitable capacity, governed, however, to some extent, by the size of the air-reservoir. It may be placed within a well or cistern and at any desired distance from the vessel C, which contains the condensed air. The water, or whatever liquid it is desired to force out of the reservoir E by the pressure of air above it, is introduced through a perforated tube, a, in the top of this reservoir, which tube receives through it the stem b of a valve, c, that opens downward or into the reservoir. The upper end of the valve-stem b has a head formed on it or attached to it, to the upper end of which a chain, e, is hooked, and this chain being connected to the short arm of a lever, G, and the other end loaded by a weight, G', it will be seen that the tubular passage a can be effectually closed by the valve c, and kept closed until it is desired to supply the reservoir with water again, when the chain is disconnected from the valve-stem, and the feed-pipe attached to the tube a and water forced through it.

Instead of disconnecting the chain from the valve-stem, as now proposed, the long arm of

the lever G may be raised, which will produce the same effect. This may be done by contrivances so constructed and operated as to obviate the necessity of approaching the reservoir E. It is necessary to shut off the communication D when the valve c is opened, otherwise the air from the reservoir C will escape through the tube a, and some difficulty would be experienced in getting water through the tube a. A stop cock, C', will serve the above purpose, applied as represented in Figs. 1 and 3, and, if desirable, another stop-cock, B', may be applied to the pipe B, leading from the base of the air-pump into the air-chamber, for preventing the air from this chamber escaping through the joints of the pump. The short pipe J, which is represented in Fig. 3, leading from a point near the bottom of the water-reservoir through its top, is the education-pipe for the water which is forced out of this reservoir, and to the outer end of said pipe a flexible hose may be attached, or an inflexible pipe leading off to a point or points wherever it is desired to conduct the water. The flow of water through these branch or service pipes may be checked at pleasure by means of cocks.

By means of the apparatus which I have above described several thousand pounds' pressure can always be kept in reserve for immediate use when required, and by means of the condensing-pump the pressure can be kept up to a maximum point.

It is not intended by my invention to keep the pump in operation during the operation of drawing water from the reservoirs, although this may be done, if desired, for I propose to force a sufficient quantity of air into the air-receiver to force out all the water or other liquid contained in the water receiver or receivers, whatever may be the number employed; and should it be found desirable to use a number of air receivers, this may be done by connecting each one with the reservoir of water by means of pipes, and the combined pressure of air in all or any one of such receivers can be caused to act upon the water in the reservoir as occasion may require.

The valve c, which I have fully described, opens downward, or toward the inside of the liquid-receiver, for the purpose of allowing liquid to be introduced into the vessel E through the opening this valve is intended to close, and at the same time preventing either the liquid or the air from escaping at said point. It will be seen that the head or shoulder b' of the valve-stem b will prevent the valve c from falling very far below its seat when the pressure of air is taken off the liquid in vessel E, and when the condensed air is again let into this vessel the pressure will force the valve c to its seat and keep it there. As this valve will thus operate by simply discharging condensed air into vessel E, or removing the pressure inside of the same, I am enabled to elevate water from the bottom of a well by submerging the vessel E

in the water of the well and locating the vessel C at any convenient point where the valve C' can be readily got at and air forced into this latter vessel by means of a condensing-pump. Now, by closing the valve C' so as to allow water to run into the vessel E, as above described, this water can be forced out of said vessel by opening the valve C' again, and by repeating the operation a large body of water may be thus elevated.

In order that the valve c may be raised to its seat by the mere pressure of air from beneath, it should be made very light. Where this is not the case, a float may be attached to it by a stem from below, so that as the reservoir fills with water the buoyancy of this float may raise the valve to its seat, where it will afterward be retained by the pressure of the air from within until the stop-cock C' is again closed, and the air within the reservoir E is allowed to escape, so as to be relieved from the extraordinary pressure to which it has been subjected. Other contrivances having a like effect may readily be substituted.

By unscrewing the cap to which the perforated tube a is fastened the interior of the vessel E can be got at for cleaning it out.

In carrying out my invention it will be necessary to provide some means for allowing the condensed air in the liquid-vessel to escape when the communication with the condensed-air vessel is closed, and for this purpose the cock which is applied to the pipe J may be opened, or a second cock may be applied to the pipe D for this purpose.

What I claim as new, and desire to secure by Letters Patent, is—

1. In a fountain which is to be operated by the elastic pressure of condensed air, the arrangement herein described—that is to say, a reservoir containing the water or other liquid to be operated upon, so contrived that it may at pleasure be subjected to or relieved from the elastic pressure of condensed air, in combination with a valve so constructed and arranged that it shall automatically close when the pressure is applied and open when it is removed, substantially in the manner and for the purpose hereinbefore set forth.

2. In a fountain which is to be operated by the elastic force of condensed air, so constructing the same that the valve through which the fluid is to be received into the reservoir shall be kept closed by the pressure of the air from within, and shall open automatically when that pressure is removed, substantially in the manner and for the purpose hereinbefore described.

Witness my hand in the matter of my application for a patent for a new and useful improvement in water-works for supplying buildings, &c., with water.

JOHN P. GRUBER.
